UNITED STATES PATENT OFFICE

2,482,743
APPARATUS FOR SCRIBING INSTRUMENTS

Ralph P. Chanfrau, Phoebus, Va.

Application September 13, 1944, Serial No. 553,857

3 Claims. (Cl. 33—75)

(Granted under the act of March 3, 1883, as
amended April 30, 1928; 370 O. G. 757)

1

The invention described herein may be manufactured and used by or for the Government for governmental purposes, without the payment to me of any royalty thereon.

This invention relates generally to drafting instruments for arranging letters in arcuate alignment, but more particularly to a device which is adapted to be used in conjunction with a printing instrument wherein the scribe is carried by a body member and is directed over the surface to be written upon by a tracer pin movable in character grooves formed in a templet and by a tail pin movable in a groove parallel to the line of lettering.

One object of the invention is to provide an easily operated device by which the templet of the scribing instrument may be placed in various positions on the arc of a circle of any suitable diameter, when it is desired to arrange the printed letters in arcuate alignment.

Another object of the invention is to provide a device of the class described which is of simple and sturdy construction, and composed of few parts which may be cheaply manufactured.

Another object of the invention is to provide a device of the class described which occupies very little space and which may be easily transported with the scribing instrument or lettering set.

Other objects and advantages reside in the details of construction and operation as more fully described and claimed hereinafter, reference being had to the accompanying drawing forming part thereof, wherein like parts are indicated by similar reference characters, and in which:

Figure 1 is a perspective view of the device showing the position of the templet in relation thereto when it is desired to arcuately align letters with their bases toward the center of curvature;

Figure 2 is a perspective view of the device showing the position of the templet in relation thereto when it is desired to arcuately align letters with their tops toward the center of curvature;

Figure 3 is a top plan view of the device showing the adjustable center plate; and

Figure 4 is an elevation of the device as projected from Figure 3.

Heretofore when the operator of a lettering set or scribing instrument as set forth above, desired to align letters in the arc of a circle, it was necessary for him to arrange the templet in a plurality of positions in order that the lettering would follow an arcuate contour. To do this accurately a circular line or lines should be drawn to direct the path of the templet or the letters or both. Even with such a careful layout inaccuracies would be prevalent, owing to the difficulties encountered in

2

arranging the templet tangent to its circular guide line or arranging the letters so that their center line would pass through the center of curvature of their arc of alignment. To facilitate accurate arcuate alignment of the letters, the device set forth herein and which is described in detail below was devised.

Referring to Fig. 1, which illustrates the device in operation, the numeral 10 indicates the sheet of paper which is being printed by means of a scribe 11, which is provided with body portion 12 having three arms 13, 14, 15 from which project, respectively, a tracer pin 16 movable in the character grooves 17 in the templet 18, a tail pin 19 movable in a groove 20 in the templet parallel to the line of lettering and a pen 21 for inking letters.

The templet which consists of a flat strip of boxwood, cellulose derivative plastic, or other suitable material, has parallel lateral edges and contains an alphabet outlined by the grooves 17 in the material.

When forming words in which the letters are aligned along a straight line the operator slides the templet 18 along the side of a triangle or the arm of a T-square, and prints one letter after another, but when forming words where the letters are in arcuate alignment it is necessary for the operator to lay out curves and move the templet to various positions as described above.

Fig. 1 illustrates the arcuate alignment of letters by the use of the herein described invention. The numeral 22 designates the entire instrument which is formed of xylonite or other suitable transparent material, and which comprises a straight edge templet guide portion 23 joined to a centrally located radial arm 24 by diagonal connecting strips 25. The guide member 23 is provided with a raised portion adjacent its outer edge which may be formed by attaching a strip of xylonite 26 thereon. The strip 26 which has parallel longitudinal edges is used as a straight edge for the templet when it is necessary to reverse the position of the letters as shown in Fig. 2 and which will be further described. A center line is inscribed on the lower surface of the guide portion 23 which serves for centering the letter to be printed.

The radial arm 24 is provided with a centrally located slotted opening 27 extending to within a short distance of either end thereof. The slot 27 functions as a guide for a sliding member 28. The sliding member 28 comprises an upper longitudinally extending plate 29 and a shorter plate 30 which are retained on the upper and lower sides 55 of the radial arm 24 by means of studs 31 which

are passed through holes in the plates 29 and 30 and the slot 27 in the radial arm 24. The upper plate 29 is drilled adjacent its ends with small holes 32 and 32'. These holes are to receive a pivot pin 33 which is used as a center of rotation about which the device is moved in an arc of a circle the radius of which depends on the setting of sliding member 28 along the radial arm 24. The plate 29 can be moved toward the straight edge 23 until the hole 32 is over the space or 10 scribing opening 34 between the straight edge and the radial arm 24 which greatly shortens the radius about which the straight edge may be turned. For further shortening of the radius holes 35 are provided along the center line 36 15 which is marked on the guide portion 23. Thus, the letters may be aligned in the arc of a very small circle.

When it is desired to arcuately align letters with their tops toward the center of curvature, 20 as shown in Fig. 2, the templet is placed against the inner edge of the strip 26 and the pen 21 is operated through the scribing opening 34 between the straight edge portion and the radial arm 24.

Having thus described my invention, what I claim as new and wish to secure by Letters Patent is:

1. A device of the character described adapted to be used with a templet-directed pantographic scribing instrument, said device being made of sheet material cut to form a head portion having a central scribing opening and a radial arm connected to said head portion by diagonal strips, upper and lower straight edges located on said head portion said lower straight edge being formed integral with the head portion of said device, and said upper straight edges being formed as parallel edges on a strip attached to said head with one of said edges being aligned with the edge formed integral with the head, said straight edges being adapted to direct the alignment of said templet when scribing respectively within and outside of said opening, and a center defining slide member supporting a pivot pin, said slide being adjustably connected to said arm and adapted to extend within said scribing opening to define a predetermined radius for the arcuate movement of said straight edges, said head portion and said straight edges being drilled along the center line thereof with a plurality of spaced holes for the reception of said centering pin to define shorter radii for the arcuate location of said straight edge.

2. A device of the character described adapted to be used with a templet-directed pantographic inscribing instrument, said device being made of sheet material cut and drilled to form a head portion provided with a plurality of centrally located holes adapted to receive a centering pin, and a centrally slotted radial arm connected to said

head portions by diagonal strips forming a scribing opening in said head portion, upper and lower straight edges located on said head portion said lower straight edge being formed integral with the head portion of said device, and said upper straight edges being formed as parallel edges on a strip attached to said head with one of said edges being aligned with the edge formed integral with the head, said straight edges being adapted to direct the alignment of said templet when scribing respectively within and outside of said opening, and a center defining slide member supporting a pivot pin, said slide being adjustably connected to said arm and adapted to extend within said scribing opening to define a predetermined radius for the arcuate movement of said straight edges.

3. A device for the arcuate alignment of characters adapted to be used with a templet-directed pantographic scribing instrument, said device being formed of rigid transparent sheet material cut to provide a head portion provided with a plurality of holes adapted to receive a centering pin, and a radial arm connected to said head portion by diagonal strips, forming a scribing opening therebetween, upper and lower straight edges positioned upon said head portion said lower straight edge being formed integral with the head portion of said device, and said upper straight edges being formed as parallel edges on a strip attached to said head with one of said edges being aligned with the edge formed integral with the head, said straight edges being adapted to direct the alignment of said templet, for the operation of said scribing instrument respectively within said scribing opening and exterior to said head portion, to thereby arcuately align characters with their top portions and bottom portions nearest the center of curvature.
